ORGAN CONSOLE

Winsor D. White, Jr., Blowing Rock, N.C., assignor to D. H. Baldwin Company, Cincinnati, Ohio, a corporation of Ohio

Filed Nov. 20, 1964, Ser. No. 82,724

Term of patent 14 years

(Cl. D56—2)

The figure is a perspective view of an organ console, showing my new design.

The side of the organ console not shown is the same as the side shown.

The dominant features of my design reside in the portions shown in full lines. The conventional keyboard is fragmentarily shown by means of broken lines.

I claim:

The ornamental design for an organ console, substantially as shown and described.
